UNITED STATES PATENT OFFICE

2,667,799

MACHINE VISE HAVING BASE-CLAMPING SCREW AND NUT ASSEMBLY FOR SECTIONAL MOVABLE JAWS

Stanley J. Rzepela, Philadelphia, Pa.

Application October 9, 1952, Serial No. 313,936

7 Claims. (Cl. 81—17)

1

This invention relates to a new and improved vise for use primarily as a work holder on a milling machine, planer, shaper, drill press, jig borer or other machine, although it could well be used also on a work bench.

In performing repeat operations on work-pieces of the same size and shape while said work-pieces are successively held in a vise, it is important that the vise be quickly operable both for clamping each work-piece and for releasing it in readiness for the next work-piece. It is also essential that speed of operation be not permitted to result in insecure holding of the work-pieces. The invention is designed to supply these needs in a simple and expeditious manner.

The improved vise embodies a fixed jaw and a movable jaw adjustable toward and from said fixed jaw, and a further object of the invention is to construct said movable jaw from two sections uniquely associated with each other, one of said sections being a work-engaging section and the other being a carrier for mounting said work-engaging section at any required position, the actual work clamping being produced by adjustment of the work-engaging section upon the carrier section. Thus, after proper setting of the carrier section, it may remain in set position while successively holding a plurality of work-pieces upon which repeat operations are being performed, and the actual gripping and release of each work-piece may be quickly and easily effected by movement of the work-engaging section upon said carrier section.

Another object of the invention is to provide a novel construction in which a threaded nut cooperates with a cam to effect the work-clamping movement of the work-engaging jaw section.

Yet another object is to provide a novel construction in which the above mentioned nut is threaded upon a set screw constituting a part of the means for holding the carrier section of the movable jaw in set position, obviating the necessity of an additional threaded member for co-action with said nut.

A further object is to provide a construction in which spring action moves the work-engaging jaw section to released position as the aforesaid nut is released.

A still further object is to provide a relatively simple and inexpensive yet a highly practical construction which will well perform all required duties and will be extremely rugged and durable.

With the above and other objects in view that will become apparent as the nature of the invention is better understood, the same consists in

2

the novel form, combination and arrangement of parts hereinafter more fully described, shown in the accompanying drawings and claimed.

In the drawings:

- 5 Figure 1 is a side elevation showing one form of the invention;
 Figure 2 is a top plan view;
 Figure 3 is a longitudinal sectional view on line 3—3 of Figure 2, showing the work-engaging section of the movable jaw engaged with a work-piece;
 Figure 4 is a similar view on line 4—4 of Figure 2, showing the work-engaging jaw section released;
 10 Figure 5 is a transverse sectional view on line 5—5 of Figure 2;
 Figure 6 is a top plan view showing a different form of construction;
 Figures 7 and 8 are longitudinal sectional views on lines 7—7 and 8—8 of Figure 6, and
 15 Figure 9 is an elevation of the slide block through which the screws of Figure 7 are threaded, part of the base being shown in broken lines in this view.
 20 25 The form of construction shown in Figures 1 to 5 will first be described. In these views a base 10 is shown which may be mounted on a machine or a work bench in any appropriate manner. This base is provided with a fixed jaw 11 at one end and is formed with a longitudinal groove 12 extending into close proximity with said fixed jaw 11. The groove 12 opens through the top of the base 10 and has a generally cylindrical form in transverse section as seen in Figure 5, providing said groove with overhanging side walls 13. A cylindrical slide block 14 is slidably received in the groove 12 and is formed with two openings 15 and 16. A relatively short set screw 17 is threaded through the opening 15, and a longer set screw 18 is threaded through the opening 16, said screws having sockets 19 in their upper ends to receive a wrench for tightening and loosening said screws. When these screws are tightened, their lower ends abut the bottom of the groove 12, as seen in Figures 3 and 5, thereby holding the slide block 14 tightly against the overhanging walls 13 and holding said block against sliding in said groove 12.
 30 35 40 45 50 A lower movable jaw section 20 rests slidably upon the base 10 over the block 14 and is formed with openings 21 through which the set screws 17 and 18 extend with clearance. The section 20 is in the form of a generally rectangular block but the top of this block is provided with two inclined cams 22 and 23, the inclined surfaces of which

are in parallel planes extending transversely of the base 10.

An upper movable jaw section 24 is carried by the lower section 20. The lower side of this upper section 24 is formed with two inclined cams 25 and 26. The cam 25 rests on the cam 22 of the lower section 20, and the cam 26 rests on the cam 23 of said lower section 20. Thus, downward forcing of the jaw section 24 will result in camming of said section toward the fixed jaw 11, and vice versa. Springs 27 are provided to shift the jaw section 24 in releasing direction, the two sections 20 and 24 being recessed at 28 (Figure 4) to receive said springs.

The jaw section 24 is formed with a slot 29 through which the set screw 18 extends, and a nut 30 and washer 31 are provided on the upper end of said set screw 18. A nut 32 and washer 33 are also provided on the upper end of the set screw 17.

To adjust the two movable jaw sections 20 and 24 as a unit, the two nuts 30 and 32 are loosened and the two set screws 17 and 18 are also loosened, whereupon the movable jaw may be slid to any desired position. Tightening of the two set screws 17 and 18 and the one nut 32 will then tightly clamp the section 20 in the selected set position. The other nut 30 is left loose until the work-piece W is to be clamped, and the springs 27 will hold the upper jaw section 24 in released position (Figure 4) as long as said nut 30 remains loose. After positioning of the work-piece W, this nut 30 is tightened, thereby causing camming of the jaw section 24 downwardly and inwardly to slidably hold said work-piece W against the base 10 and the fixed jaw 11. When the required operation has been performed on the work-piece, mere loosening of the nut 30 will cause the jaw section 24 to be spring-moved to released position, permitting quick removal of said work-piece and insertion of the next.

To prevent pivotal movement of the upper jaw section 24 about the screw 18, said section is provided with side flanges 34 which slidably straddle the lower section 20, as seen in Figures 1 and 5.

A construction very similar to that shown in Figures 1 to 5 is disclosed in Figures 6 to 9. The groove 12a of the base 10a, however, is of T-shaped cross section and the slide block 14a is of corresponding shape. Also, the lower jaw section 20a is provided with a single inclined cam 22a, and the upper section 24a has a single cam 25a cooperable with said cam 22a. Also, the two sections 20a and 24a are slidably dove-tailed together as seen at 35. Otherwise, the construction shown in Figures 6 to 9 is practically identical with that of Figures 1 to 5 and requires no further explanation.

From the foregoing and the accompanying drawings it will be seen that novel and advantageous construction has been provided for carrying out the desired ends. However, it is to be understood that variations may be made within the scope of the invention. Also, the device is not restricted to use in a horizontal position but may occupy any of various positions according to the uses to which it is to be put.

I claim:

1. A vise comprising a base having a fixed jaw, said base having a groove in its upper side and extending toward said fixed jaw, said groove having overhanging side walls, a slide block in said groove, a set screw threaded through said slide block to abut the bottom of said groove when tightened, thereby forcing said guide block

against said overhanging side walls, said set screw projecting above said base, a lower movable jaw section resting slidably upon said base and having an opening through which said set screw extends with clearance, the upper side of said lower section being provided with an inclined cam, an upper movable jaw section having a slot through which said set screw passes, said upper section having a cam cooperable with the aforesaid cam to cause movement of said upper section toward said fixed jaw when said upper section is forced toward said base, and a nut threaded on the upper end of said set screw for forcing said upper section toward said base.

2. A structure as specified in claim 1; together with spring means acting on said upper section and reacting on said lower section for moving said upper section in releasing direction when said nut is loosened.

3. A structure as specified in claim 1; together with a second set screw threaded through said slide block to abut said bottom of said groove when tightened, said lower section having an opening through which said second set screw extends with clearance, and a second nut threaded on the upper end of said second set screw for coaction with the latter in clamping said lower section to said base.

4. A vise comprising a base having a fixed jaw, said base having a groove in its upper side and extending toward said fixed jaw, said groove having overhanging side walls, a slide block in said groove, a set screw threaded through said slide block to abut the bottom of said groove when tightened, thereby forcing said guide block against said overhanging side walls, said set screw projecting above said base, a lower movable jaw section resting slidably upon said base and having an opening through which said set screw extends with clearance, the upper side of said lower section being provided with an inclined cam, a nut threaded on the upper end of said set screw for coaction therewith in clamping said lower section against said base, an upper movable jaw section having a cam at its lower side resting on said cam of said lower section to cause movement of said upper section toward said fixed jaw when said upper section is forced toward said base, and manually operable means for forcing said upper section toward said base.

5. A vise as in claim 4, wherein the upper section has parallel side flanges slidably straddling said lower section.

6. A vise as in claim 4, wherein said cams of said upper and lower sections are slidably dove-tailed together.

7. A vise comprising a base having a fixed jaw, said base having a groove in its upper side and extending toward said fixed jaw, said groove having overhanging side walls, a slide block in said groove, a set screw threaded through said slide block to abut the bottom of said groove when tightened, thereby forcing said guide block against said overhanging side walls, said set screw projecting above said base, a lower movable jaw section resting slidably upon said base and having an opening through which said set screw extends with clearance, the upper side of said lower section being provided with an inclined cam, a nut threaded on the upper end of said set screw for coaction therewith in clamping said lower section against said base, an upper movable jaw section having a cam at its lower side resting on said cam of said lower section to cause movement of said upper section toward said fixed jaw when said upper section is forced

5

toward said base, and wrench operated threaded means for forcing said upper section toward said base.

STANLEY J. RZEPELA.
